UNITED STATES PATENT OFFICE

2,301,411

PLUG TERMINAL FITTING

Samuel M. Kass, Philadelphia, Pa.

Application July 17, 1940, Serial No. 345,935

1 Claim. (Cl. 173—322)

My present invention relates to plug terminals for flexible two-wire electric conductors, herein called insulated electric two-wire cords, widely used for example in energizing household electric appliances such as electric toasters, electric irons, electric pads and the like, from any convenient house outlets, and the invention is more specifically directed to the terminal between the cord and appliance.

Further purposes will appear in the specification and in the claim.

I have elected to illustrate a few forms only of my invention, selecting forms however and minor variations thereof that are practical and efficient in operation and which well illustrate the principles involved.

Figure 1 is a face elevation illustrating one embodiment of my invention.

Figure 2 is an edge elevation, in half section of Figure 1.

Figure 3 is a view corresponding in general to Figure 1 but showing a somewhat different form.

Figure 4 is an edge elevation, in part in section, of Figure 3.

Figure 5 is a sectional elevation of Figure 6 taken upon the line 5—5 thereof.

Figure 6 is a face elevation of a different form.

The structure is described in illustration and not in limitation.

The split body members 10 and 11 receive at the rear a cord 16 and are held together by bolts 26 and 27.

The resilient guard 28 is mounted upon outwardly projecting split wedge members located between a ring 29 and the cord and which cooperate with the ring in externally connecting and supporting the cord from the ring.

In the illustrations of Figures 1 and 2 my ring along with arms 30 and 31 make up a ring bracket. The arms 30 and 31 are supported by opposite ends of the bolt 26. The arms thus complete a U support or loop having a ring at the middle of the U. The bolt 26 is threaded at 32 into the arm 31 which acts as a nut for the bolt.

The ring externally fits threaded taper members (wedges) 33 and 34 which embrace opposite surfaces of the cord 16. At their lower edges the wedges are shown as out of contact with the cord. The wedges engage split sleeve parts or shoes 35 and 36 which grip opposite faces of the cord at 37 and preferably receive and support a resilient guard fragmentarily shown at 28.

The shoes 35 and 36 may be of any suitable material, as fiber or metal and preferably are performed at their outer ends to cooperate with the spring guard 28 to receive and support the guard.

The taper members 33 and 34 are shown with inwardly extending teats 38 to indent into or to be received within indentations of the sleeve parts 35 and 36.

5 As illustrated the members 33 and 34 taper toward the terminal and at their outer ends are provided with wings 39 to facilitate threading into the ring 29.

In Figures 3 and 4 the ring bracket is kept from angular movement about the bolt 26 by shoulders 40 and 41 in arms 30', 31'. In these figures the ring 29' has a tubular extension along the length of the relatively split wedge or taper members 33' and 34'. Shoe 36' is seen in Figure 3.

10 I may facilitate assembly and somewhat simplify the construction by using a single arm instead of the two arms 30 and 31, preferably making it somewhat heavier than with the two-arm construction and securing it firmly from any angular movement about the bolt 26 by extending it for additional fastening at the bolt 27.

In Figures 5 and 6 the ring bracket is illustrated as an L shaped strip of flat or die stamped material adequately heavy or strong to firmly support its ring 29² along 10' by the long arm 31². It is shown both as fitting laterally into the body 10' flush therewith and as tapped to receive the threaded end of the bolt 27, and to receive the bolt 26.

15 The relatively split taper or wedge members 33² and 34² between the ring 29² and cord 16, as illustrated taper away from the terminal and have a smooth longitudinal sliding engagement with the interior of the ring 29².

20 The taper members 33² and 34² throughout their length engage opposite sides of the cord 16 and at their outer ends are formed at 42 to receive and expand and hold the upper end of the spring guard.

25 Having thus described my invention what I claim as new and desire to secure by Letters Patent is:

30 A terminal for one end of a two-wire electric cord, comprising a longitudinally split body adapted to enclose electric terminal contacts, a bolt holding the split body portions together, a ring adapted to surround the cord, inwardly yieldable taper means for gripping the cord at one point, longitudinally movably mounted in the ring whereby it may be moved in respect to the ring to cause it to grip the cord at one point, shoes at a second point surrounded by the taper means and arms extending from the opposite sides of the ring and secured thereto to engage the bolt on opposite sides of the body to secure the arms to the body.

SAMUEL M. KASS.
